UNITED STATES PATENT OFFICE.

JOHN S. BAKER, OF LOS ANGELES, CALIFORNIA.

INTERLOCKING MECHANISM FOR VOTING MACHINES.

Application filed July 21, 1924. Serial No. 727,376.

To all whom it may concern:

Be it known that I, JOHN S. BAKER, a citizen of the United States, residing at Los Angeles, in the county of Los Angeles and State of California, have invented certain new and useful Improvements in Interlocking Mechanism for Voting Machines; and I hereby declare that the following is a full, clear, and exact description thereof, reference being had to the accompanying drawings, which form part of this specification.

This invention is an improvement in interlocking mechanisms for vote registering machines, or vote or ballot counting machines and the like, and is particularly designed for use in connection with a ballot counting machine such as shown and described in my U. S. Letters Patent No. 1,507,548, dated September 2, 1924. The principal object of the invention is to provide a novel interlocking mechanism for such machines, which may be readily "set up", or adjusted, for election, is simple in construction and operation, has a relatively wide interlocking range, and which will be positive in its operation.

Another object is to provide an interlocking mechanism for vote registering machines, said mechanism having a wide interlocking range, the interlocking members comprising relatively short changeable cam members pivoted and swingable between certain limits, thereby decreasing frictional losses, and rendering the mechanism sensitive and positive in operation, requiring less operating power, and obtaining a relatively wide interlocking range with the use of comparatively short swingable interlocking cams.

A further object of the invention is to provide a novel interlocking mechanism in which the pivoted cams which are depressed by the vote registering members of the machine, contact with pivoted cam blades having limited swinging movement by reason of certain set "stops" whereby only a predetermined number of the vote registering members of the machine may be depressed at the same time, means being provided for grouping any of the registering members as desired. The cam members are either interlocking cams or neutral cams and are

interchangeable at will, so that by removing a loosely mounted swingable interlocking cam and replacing same with a neutral cam, the interlocking system may be readily and easily adjusted at will, the simplicity of adjustment being one of the features of my mechanism.

Other minor objects of the invention will be hereinafter set forth.

I will explain the invention with reference to the accompanying drawings which illustrate one practical embodiment thereof to enable others to adopt and use the same, and will summarize in the claims the novel features of construction, and novel combinations of parts, for which protection is desired.

In the drawings:

Figure 1 is a plan view, partly broken away, of the mechanism.

Figure 2 is a side elevation of the mechanism.

Figure 3 is a front elevation of the mechanism, towards the rear.

Figure 4 is a plan view of the electrical circuit makers and breakers.

Figure 5 is a section on the line 5—5, Figure 4.

Fig. 6 is a side view of the interlocking U-shaped block.

Fig. 7 is an end view thereof. Fig. 8 is a side view of the spacer U-shaped block. Fig. 9 is an end view thereof.

As shown in the drawings, the entire interlocking mechanism is assembled on a base frame or plate 1, adapted to rest, preferably in horizontal position, in the machine upon tracks 1^a, which tracks are disposed horizontally below the lower ends of the registering members (not shown), or detector pins of the machine such as described in my aforesaid application, said tracks 1^a being bolted or otherwise secured to the uprights M' of the machine. The base frame or plate 1 may be locked in adjusted position on said tracks 1^a by means of thumb screws 1^b or the like.

The base frame 1 is provided with evenly spaced upstanding bosses 1^c on its upper face, adjacent the front and rear edges thereof, said bosses being provided with

bores adapted to receive the guide posts or studs 2^a of the parallel frames 2, which carry the cam bracket posts 2^b, whereby the frames 2 which are preferably angle bars, and the studs 2^a thereof, may move freely up and down in said bosses 1^c. Tracks 1^a are likewise provided with depending bosses 1^d on their lower faces, which bosses 1^d are adapted to register with the upstanding bosses 1^c of frame 1, when said frame 1 is properly positioned on said tracks 1^a, bosses 1^d being likewise provided with bores, adapted to receive and retain the studs 3^a of follower plate 3 (hereinafter referred to) so that by raising the follower plate 3, the studs 3^a in the bosses 1^d will abut the lower ends of the posts or studs 2^a in bosses 1^c, and will thereby raise the frames 2 for the purpose hereinafter described.

20 Follower plate 3 slides freely up and down in bosses 1^d but is not attached to the plate frame 1, so that the frame 1 may be moved without interfering with the follower plate 3. The follower plate is held up in operative position and receives its motion from a suitable connecting rod 3^b actuated by a cam and lever from a shaft of the machine (not shown) mounted below said follower plate, and the movement of the follower plate 3 is so limited that the studs 3^a cannot drop out of the bosses 1^d of tracks 1^a. When follower plate 3 is in its "down" position the upper ends of studs 3^a will be disposed slightly below the upper surfaces of tracks 1^a.

35 Upon each frame 2 is a row of evenly spaced upstanding hollow bearing posts 2^b, which posts are preferably riveted to said frame 2 (as shown in Figs. 2 and 3) and on each bearing post 2^b is loosely mounted a tubular member 4, having its upper end closed on which end the member 4 receives its depression stroke, said members 4 being normally retained in elevated position on said posts by means of coil springs 5, which fit within the hollow bearing posts 2^b, and members 4, and contact with the frames 2 and upper closed ends of members 4.

45 Integral with, or attached to, each tubular member 4, is an arm 4^a, extending horizontally and radially therefrom, and depending from the outer ends of said arms 4^a, and attached thereto in any desired manner are the interlocking and neutral cams 10 and 11 hereinafter referred to. One tubular member 4 is disposed directly below the lower end of each registering member or detector pin (not shown) of the machine, so that when the registering members are in their normal elevated positions the members 4 will also be in their elevated positions, and the interlocking mechanism inactive, but when the registering members are depressed, the related members 4 will likewise be depressed, and the interlocking mechanism put into action.

Drilled into base plate 1 are a plurality of rows of evenly spaced bearing holes 1^e in which the cam blades 6 and 7 are pivoted at their ends, on studs 6^a and 7^a respectively, whereby the cam blades 6 and 7 may swivel 70 or pivot freely upon said frame 1. The rows of holes 1^e are preferably disposed directly below the rows of studs 2^b on the angle frames 2, but the individual holes 1^e in said rows are preferably disposed intermediate 75 adjacent studs 2^b, as shown in Figures 2 and 3.

Cam blades 6 and 7 are identical in construction with the exception that the bearing studs 7^a of cam blades 7 extend below the base plate 1, and on the lower end of said studs are detachably attached transfer gear segments 9, the pitch radii of said gear segments 9 being equal to half the distance between adjacent rows of holes 1^e, so that when the gear segments 9, attached to cam blades 7 of adjacent rows, mesh (as shown in Figure 1) the motion of the cam blades 6 and 7 of one row will be imparted or transferred to the cam blades 6 and 7 of the adjacent row, thereby combining the blades of a plurality of rows into one single group. Gear segments 9 are interchangeable on the bearing studs 7^a on any cam blade 7, and are preferably detachably attached to said studs 7^a by means of key washers 7^b, and screws 7^c (as shown in Fig. 2).

Also, suitably spaced in rows in the base frame 1 are blade stop holes 1^f, adapted to receive stops 8 for limiting the swinging movement of the blades 6 and 7 of each group and which fit in said holes 1^f, said stops 8 being held in position therein by means of screws 8^a. The stops 8 are interchangeable in any hole 1^f, also the cam blades 6 and 7 are interchangeable in any of the bearing holes 1^e.

The members 4 are mounted on posts 2^b so that the same may slide freely up and down, and may pivot thereon, while the cams 10 and 11, which are attached to the arms 4^a of said members 4 are adjusting themselves between the blades 6 and 7 during the interlocking operation, which operation merely comprises the forcible compression of the members 4 (by the registering members or detector pins of the machine) with their cams 10 or 11, to force said cams down between the adjusted blades 6 and 7 of the various groups.

Cams 10 are the interlocking cams, and cams 11 are neutral cams, and at least one interlocking cam 10 is required for each group, otherwise there will be no interlocking action. The wide parts of cams 11 and the narrow portions of cams 10 are of the same width, which width is equal to the normal distance between adjacent blades 6 or 7, the wide portions, however, of inter-

locking cams 10 are greater than the normal distance between adjacent blades 6 or 7.

Referring to the group of three cams, (in Fig. 2) two neutral cams 11, and one interlocking cam 10 is shown between stops 8 which stops limit the swing of the group of blades 6 or 7. The neutral cams 11 may be depressed between the blades 6 without moving said blades since the overall widths of said cams 11 are just equal to the normal distances between adjacent blades 6 or 7. The wide portions of interlocking cams 10 however will not, when depressed, pass between the blades without separating same, or pivoting said blades, since the overall widths of cams 10 are greater than the normal distance between adjacent blades. When the members 4 of this group are depressed by their respective registering members, the blades 6 will be forced apart, and will pivot on their studs between the stops 8 and the smaller portions of cam 11 adjacent cam 10 will be forced against the adjacent blade 6 to allow room for the depression of cam 10. There will however, still be room between the blades for the other cam 11 to pass between the blades. This group of three members 4 is set up to allow for two candidates to be voted for, since two cams only may pass or be depressed, the narrow part of one cam 11 compensating for the passing of the wide part of cam 10.

If any of the cams 10 or 11 should become stuck between the cam blades 6 or 7, after the depression thereof or interlocking operation, and if the springs 5 in the members 4 are not strong enough to lift the weight of the cams 10 and 11 so stuck, by raising the follower plate 3, as above described, and the frames 2 about a quarter of an inch, the members 4 will thereby be raised, as above described, to loosen said stuck cams. When plate 3 is lowered, frames 2 immediately drop into their normal positions, after leaving the cams 10 and 11 in their normal positions. This feature of raising the frames 2 by means of follower plate 3, is provided merely for safety, and to assure that no cams 10 or 11 remain stuck between cam blades 6 and 7 after the interlocking operation.

In addition to the above mechanism I have provided an auxiliary mechanism to be used only when the mechanism is set up to include more than one group, but only one candidate for all the groups may be voted, such as at presidential elections where the voter may either vote directly for the president in one group, or may vote for one elector candidate, but cannot vote for both simultaneously, my auxiliary mechanism preventing registering of votes for a candidate in more than the one group.

While the interlocking mechanism above described prevents the registering of irregu-

lar votes in the respective groups, it would not prevent registering the irregularly voted groups, but my auxiliary mechanism will prevent such registering.

The auxiliary mechanism consists of small 70 interlocking U-shaped blocks 12 (Figs. 6 and 7) and U-shaped spacer blocks 13 (Figs. 8 and 9), which blocks are slidably mounted on vertical legs of said angle frames 2. Blocks 12 and 13 are interchangeable, and may be of tongue and groove construction to hold same in alignment on said frames 2. Blocks 12 are provided with small projections 12^a extending from one lower edge, said projections being adapted to slide under the lower edge of an adjacent member 4 when shifted into engagement therewith as shown in Figure 3. At one end of each row of blocks 12, 13, is a coil spring 14, adapted to normally shift the row of blocks 12, 13 out of engagement with the members 4 of said row, while at the other end of each row is a contacting member 15 which is also slideable on the frame 2 but is permanently attached thereto by means of a stud 2^a on said frame 2 engaging a slot 15' in said member 15.

Mounted opposite each member 15 is a horizontally disposed plunger 16 pivoted on the end of an arm 17, which arm 17 is yieldably mounted on a rock shaft 18 journaled in the frame of the machine. At one end of shaft 18 is keyed rocker arm 19, which is hingedly connected to the core of an electric solenoid 20 so that when the solenoid is excited arm 19 will rock shaft 18, and thereby force all of plungers 16 against members 15, whereby each row of blocks 12 and 13 will be shifted on said frames 2 until the lugs 12^a of blocks 12 pass under the bottom edges of members 4, thereby preventing the members 4 of said rows from being depressed, the blocks 12 and 13 being held in the above position until after the depression or interlocking stroke, and thereby preventing the registering of the votes in the rows so locked. As soon as the solenoid circuit is broken, springs 14 push the blocks 12, 13, of their respective rows back out of engagement with members 4.

If the lugs 12^a on blocks 12 should strike member 4 of one row and could not thus be shifted then the arm 17 for said row will yield on shaft 18 to compensate for the movement of rock shaft 18, but the other arms 17 for the other rows will nevertheless function. The core of solenoid 20 extends down through the coil and is of such length that the center of the core is below the center of the coil, so that when the solenoid circuit is closed, and the solenoid excited, the core will be raised, thereby rocking arm 19 and shaft 18, and actuating the plungers 16 shifting the blocks 12 and 13 into operative position above described. Arm 19, and

the head of the core are preferably made of brass and are therefore unattracted by the solenoid.

- 5 The electrical contacts for controlling the solenoid 20 are placed in the voting or vote registering machine in such position that they will be directly operated by the voting keys or detector pins of the machine, said contacts being shown in Figures 4 and 5.
- 10 Two or more base members 21, preferably of insulating material, may be mounted in any convenient part of the machine, and the electrical conductors 22^a, 22^b, 22^c are inlaid in same and spaced 70
- 15 apart. Conductor 22^a is the live conductor and may be directly connected with a source of electric current, while conductors 22^b, and 22^c are the "dead" conductors. Conductor 22^a is disposed so as to contact with 75
- 20 each of the contact disks 23 when the same are operated by their respective registering members, except the contact disks 23^a in the presidential group, as shown in Figure 4.
- Conductor 22^b is the intermediate conductor 80
- 25 which receives its current through the contact disks 23^a from 22, while conductor 22^c is the solenoid conductor and receives its current from conductor 22^b, contacts being made from one conductor to the 85
- 30 other by means of contact disks 23, which bridge the gaps between conductors, said discs being operated by and with the voting keys or detector pins V of the machine, as shown in Figures 4 and 5. If a vote is cast 90
- 35 for the President, a disk 23^a will bridge conductors 22^b and 22^c, but since these conductors are both normally "dead," no current will pass to the solenoid 20, thereby allowing 95
- 40 the registering of the president vote. But if a vote is cast for any elector simultaneously when voting for President, a disk 23 will drop and make circuit between 22^a and 22^b which operation will complete the solenoid circuit through wire 22^c and will 100
- 45 rock shaft 18. If, however, one votes for the electors, and should drop a disk 23 only, then no current can get to conductor 22^c and the solenoid will not be excited. In other words, one must vote for the two groups 105
- 50 and cause a disk 23 and a disk 23^a to drop in order to make a complete circuit to the solenoid 20 to interlock the groups.

I do not limit my invention to the exact form shown in the drawings for obviously changes might be made therein without departing from the scope of the invention. My novel interlocking mechanism is simple in construction and operation, is positive in action, and may be readily adapted to suit the particular machine with which the mechanism is to be used.

I claim:

1. In an interlocking system for vote registering machines, a series of cam members and a series of intermediate members, the

cam members acting at angles to the intermediate members, and the intermediate members being freely mounted at their ends and the cam members being freely mounted at their sides so that all said members may 70 swivel in their bearings during interlocking operation.

2. In an interlocking system for vote registering machines, a series of parallel swingable members, and a series of changeable members interposed at right angles to the first mentioned members, all said members being freely pivoted so that they may adjust themselves during interlocking. 75

3. In an interlocking system for voting machines, a plurality of cam members, and cam blades, said cam members being swingable horizontally and movable vertically, and said cam blades being adapted to swivel laterally under the action of the cam members passing therebetween during interlocking. 80

4. In an interlocking system for voting machines, a plurality of cam members; a plurality of cam blades; said cam members being mounted to swing horizontally and to move up and down, and said cam blades being mounted to swivel laterally under the action of the cam members passing at right angles therebetween during interlocking. 85

5. In an interlocking system for voting machines; a plurality of posts; a plurality of cam members adapted to work freely up and down and swivel on said posts; spring means to hold the cam members in normal position; and interposed swiveled members which are also freely mounted. 90

6. In an interlocking system for voting machines, a series of posts, a series of cam members slipped over and working freely up and down and swiveling on said posts; springs to hold the cam members in their normal positions, and interposed blades freely mounted and adapted to swivel from one end. 100

7. In an interlocking system for voting machines, a plurality of posts, cam members mounted on said posts so that they may swing horizontally and move up and down on said posts; and means to automatically loosen any members which may become stuck during the interlocking operation. 110

8. In an interlocking system for voting machines, a series of posts, a series of cam members mounted on the posts and adapted to swivel and move up and down thereon, and a frame adapted to be raised to loosen any members which may become stuck during the interlocking operation. 120

9. In an interlocking system for voting machines; a plurality of members; means for dividing the members into individual groups, means for combining a plurality of groups for one office, and means for pre- 130

- venting the simultaneous operation of more than one group if it is attempted to vote for candidates in more than one group.
10. In an interlocking system for voting machines, a plurality of members, means for dividing the members into individual groups, and electrically operated interlocking means to prevent the simultaneous registering of votes in more than one group,
- 10 11. In an interlocking system for voting machines, a plurality of members capable of swiveling and moving up and down,
- 15 means for dividing the members into individual groups, and interlocking means to prevent the simultaneous registering of votes in more than one group, if it is attempted to vote for candidates in more
- 20 than one group.
12. In an interlocking system for voting machines, a plurality of members capable of swiveling and moving up and down, means for dividing the members into individual groups, means for combining two groups for one office, and interlocking means to prevent the simultaneous registering of votes in more than one group, if it is attempted to vote in more than one group.
- 25 13. In an interlocking system for voting machines, a plurality of members; means for dividing the members into groups; with means for preventing the simultaneous operation of the members of more than one group, if it is attempted to vote for candidates in several individual groups while permitting voting of any one of the individual groups.
- 30 14. In an interlocking system for voting machines, a plurality of members; means for dividing the members into groups, means for preventing the simultaneous voting operation of several groups if it is attempted to vote in more than one group, but permitting operation of the members in any one group if the voting is done in only one group.
- 35 15. In an interlocking system for voting machines, a plurality of members and means for dividing the members into groups, means for operating the members of any group; and means for preventing the simultaneous voting operation of members of more than one group if it is attempted to vote for candidates in several individual groups, but permitting operation of the members in any one group if the voting is done in only one group.
- 40 16. In an interlocking system for voting machines, a plurality of members, means for dividing the members into individual groups, and means for preventing the simultaneous operation of more than one group if it is attempted to vote for candidates in more than one group.
- 45 17. In an interlocking system for vote registering machines, cam members and intermediate members, both members being freely mounted so that they may swivel in their bearings and have a sweeping motion 70 while interlocking; means for dividing the members into groups, and means for preventing the operation of members in more than one group, if it is attempted to vote for candidates in more than one group at 75 one time.
18. An interlocking mechanism for vote registering machines, comprising a plurality of pivoted cam members and a plurality of pivoted cooperating cam blades having a 80 limited swinging movement, said cam and blade members being adapted to swing in parallel horizontal planes, and having their pivots disposed in the same vertical plane.
19. An interlocking mechanism for vote 85 registering machines, comprising a plurality of cam members, and a plurality of cooperating cam blades, said cam and blade members being pivoted at their ends, all of said pivots being disposed in the same vertical plane, and said blade members having a limited swing.
20. An interlocking mechanism for vote 90 registering machines, comprising a plurality of pivoted cam members adapted to be depressed, and a plurality of pivoted cooperating cam blades having a limited swinging movement, whereby when said cams are depressed the blades will arrest the downward movements of some of said cams, said 100 pivots being disposed in the same vertical plane.
21. An interlocking mechanism for vote 105 registering machines, comprising a plurality of pivoted cam members adapted to be individually or simultaneously depressed, and a plurality of pivoted cooperating cam blades having a limited swinging movement and adapted to pivot when said cams are depressed to arrest the movements of said 110 cams, said pivots being disposed in the same vertical plane.
22. An interlocking mechanism for vote 115 registering machines, comprising a plurality of pivoted cam members; and a plurality of pivoted cooperating cam blades; one or more of said cams being of greater width than the normal distance between adjacent blades, and the remaining cams being of width equal to the normal distance between 120 blades; whereby the movements of the one or more wider cams will be arrested.
23. An interlocking mechanism for vote 125 registering machines comprising a plurality of pivoted cam members adapted to be depressed; and a plurality of pivoted cooperating cam blades having a limited swinging movement; one or more of said cams having portions greater in width than the normal distance between adjacent blades, and the 130

remaining cams being of width equal to the normal distance between blades; whereby when said cams are depressed said blades will pivot between their swinging limits and arrest the movement of the said one or more wider cams.

24. An interlocking mechanism for vote registering machines having registering members adapted to be depressed for each 10 respective candidate to be voted for, comprising a plurality of pivoted cam members respectively disposed below said registering members and adapted to be depressed thereby; and a plurality of pivoted cooperating 15 cam blades below and intermediate said cams and having a limited swinging movement, one or more of said cams being of greater width than the normal distance between adjacent blades, and the remaining 20 cams being of width equal to the normal distance between blades, whereby when said cams are depressed said blades will be caused to pivot and arrest the movements of the one or more wider cams.

25. 25. An interlocking mechanism for vote registering machines, comprising a plurality of evenly spaced posts; cam members pivoted on said posts respectively and adapted to be depressed thereon; means for normally 30 maintaining said cams in elevated position; a plurality of pivoted cam blades disposed vertically below and intermediate said cams; and means for limiting the swinging of said blades, whereby when said cams are depressed the blades will pivot between said 35 limits and arrest the downward movements of some of said cams.

26. An interlocking mechanism for vote 40 registering machines, comprising a plurality of evenly spaced posts; cam members pivoted on said posts respectively and adapted to be depressed thereon; means for normally maintaining said cams in elevated position; a plurality of pivoted cam blades 45 disposed below and intermediate said cams; and stops for limiting the swing of said cam blades; one or more of said cams having portions of greater width than the normal distance between adjacent blades, the remaining 50 cams being of width equal to the normal distance between blades whereby when said cams are depressed the blades will pivot between said stops to arrest the downward movements of the one or more wider cams.

27. An interlocking mechanism for vote 60 registering machines having a plurality of registering members adapted to be respectively depressed for each candidate to be voted for; comprising a plurality of evenly spaced posts mounted in the machine below said register members respectively; interchangeable cam members pivoted on each of said posts and adapted to be depressed by 65 said registering members; means for nor-

mally maintaining said cams in elevated position; a plurality of interchangeable pivoted cam blades disposed below and intermediate said cams; and stops for limiting the swing of said blades; one or more 70 of said cams having portions of greater width than the normal distance between adjacent blades, the remaining cams being of same width as the normal distance between blades; whereby when said cams are depressed the blades will pivot between said 75 stops to arrest the downward movements of the one or more wider cams.

28. An interlocking mechanism for vote 80 registering machines, comprising a frame adapted to be reciprocably mounted in the machine; a plurality of evenly spaced pivoted cams reciprocably mounted on said frame; a plurality of pivoted cam blades disposed below and intermediate said cams 85 and adapted to cooperate with said cams, and means for raising said frame to disengage said cams from the blades.

29. In mechanism as set forth in claim 28, 90 said means comprising a vertically reciprocable member mounted in the frame of the machine, said member having posts thereon adapted to engage the said frame whereby when said member is raised said frame will be raised and the cams will be disengaged 95 from said blades.

30. An interlocking mechanism for vote 100 registering machines, comprising a frame adapted to be vertically reciprocably mounted in the machine; a plurality of evenly spaced posts mounted upon said frame; a plurality of cams reciprocably mounted on said posts; means for maintaining said cams normally elevated; a plurality of cam blades disposed below and intermediate said cams, and adapted to cooperate with said cams; and means for raising said frame to disengage said cams 105 from the blades.

31. In mechanism as set forth in claim 110 30, said means comprising a vertically reciprocable member mounted in the frame of the machine, said member having posts thereon adapted to engage the under side of said frame to elevate same to raise the 115 frame and the cams thereon out of engagement with said blades.

32. An interlocking mechanism for vote 120 registering machines, comprising a frame adapted to be vertically reciprocably mounted in the machine; a plurality of evenly spaced posts mounted on said frame; a plurality of cams reciprocably mounted on said posts; spring means for maintaining said cams normally elevated; a plurality of cam blades disposed below and intermediate said cams, and adapted to cooperate with said cams; and a vertically reciprocable member mounted in the frame of the machine, said member having posts thereon 125 130

- adapted to engage the under side of said frame whereby when said member is elevated the frame and cams thereon will be raised out of engagement with said blades 5 to release any cams which may be stuck between said blades.
33. An interlocking mechanism for vote registering machines, comprising a plurality of rows of pivoted cam members adapted 10 to be depressed; a plurality of rows of pivoted cooperating cam blades for arresting the movements of said cams; means for combining blades of each row into one or more individual groups; means for combining blades of adjacent rows into one or more groups; and interlocking means for preventing the registering of votes in more than one group.
34. In mechanism as set forth in claim 33, 20 said means for combining the blades in adjacent rows into groups comprising intermeshing gear segments mounted on the pivots of adjacent blades at the same end of adjacent rows of blades, whereby the motion of the blades of one row will be transferred to the blades of adjacent rows, and adjustable stops adapted to be placed at the free ends of each group to limit their swinging movements.
35. In mechanism as set forth in claim 33, 30 said interlocking means for preventing registering of votes in more than one group, comprising blocks slidably mounted adjacent said cams and having portions adapted 35 to prevent the depression of said individual cams; means for normally holding said blocks disengaged from said cams; a shaft mounted transversely to blocks, plungers eccentrically and yieldably mounted on said 40 shaft opposite said blocks; and means for oscillating said shaft to engage the blocks with said cams to prevent registering of any votes in more than one group, and to prevent a vote being registered in any other group while a vote is being registered in one group.
36. In an interlocking mechanism for vote registering machines, comprising a plurality of rows of pivoted cam members adapted 50 to be depressed; a plurality of rows of pivoted cooperating cam blades; means for dividing the cams and blades of the same rows into individual groups; means for combining the cams and blades of adjacent rows into different groups; and interlocking means for preventing the registering of votes in more than one group, one or more of said cams in each group having portions of greater width than the normal distance 55 between adjacent blades, the remaining cams in said groups being of same width as the normal distance between said blades; whereby when said cams are depressed the movement of the one or more wider cams in each 60 group will be arrested.
37. In mechanism as set forth in claim 36, said means for combining the cams and blades of adjacent rows into groups comprising intermeshing gear segments mounted on the pivots of adjacent blades at the 70 same end of adjacent rows of blades, whereby the motion of the blades of one row will be transferred to the blades of adjacent rows, and adjustable stops adapted to be placed at the free ends of each group to 75 limit their swinging movement.
38. In mechanism as set forth in claim 36, 80 said interlocking means for preventing registering of votes in more than one group, comprising blocks slidably mounted adjacent each row of cams and having portions adapted to prevent the depression of said individual cams; means for normally holding said blocks disengaged from said cams; a shaft mounted transversely to said blocks; 85 plungers eccentrically and yieldably mounted on said shaft adapted to contact with blocks; a solenoid, an arm on said shaft operated by the core of said solenoid; and means for exciting said solenoid to engage 90 said blocks with said rows of cams whereby when a single cam in any group is depressed said solenoid will be inoperative, and when cams in two or more groups are simultaneously depressed said solenoid will shift 95 the blocks into engagement with said cams to prevent registering of any of said votes.
39. In an interlocking system for vote registering machines, a series of cam blades 100 each adapted to swivel in the plane of the blades; cams disposed intermediate the blades and adapted to swivel in a plane parallel with the series of blades; and means for limiting the swing of the blades.
40. In an interlocking system for vote 105 registering machines, a series of cam blades each adapted to swivel in the plane of the series of blades; a series of cams adjacent said blades, said cams being disposed intermediate the blades and adapted to swivel in 110 a plane parallel with the series of blades; and means for limiting the swing of the blades; said cams being selectively depressible.
41. In an interlocking system for vote 115 registering machines, a plurality of rows of cam blades each blade being adapted to swivel in the plane of the blades; a plurality of rows of cams adjacent said blades, 120 said cams being disposed intermediate the blades and adapted to swivel in a plane parallel with the rows of blades; and means for limiting the swing of the blades; said cams being selectively depressible.
42. In an interlocking system for vote 125 registering machines, a series of cam blades each adapted to swivel in a horizontal plane; a series of cams above said blades, said cams being disposed intermediate the blades and adapted to swivel in a horizontal plane;

means for limiting the swing of the blades; and means for normally maintaining the cams in raised position.

43. In an interlocking system for vote registering machines, a series of cam blades each adapted to swivel in a horizontal plane; a series of cams above said blades, said cams being disposed intermediate the blades

and adapted to swivel in a horizontal plane; means for limiting the swing of the blades; 10 and means for normally maintaining the cams in raised position; cams being selectively depressible.

In testimony that I claim the foregoing as my own, I affix my signature.

JOHN S. BAKER.
